ATTORNEYS.

UNITED STATES PATENT OFFICE.

THOMAS F. JONES, OF ABERDEEN, OHIO, ASSIGNOR OF ONE-HALF OF HIS
RIGHT TO T. K. BALL & SON, OF MAYSVILLE, KENTUCKY.

PLOW.

SPECIFICATION forming part of Letters Patent No. 231,913, dated September 7, 1880.

Application filed February 28, 1880.

To all whom it may concern:

Be it known that I, T. F. JONES, of Aberdeen, in the county of Brown and State of Ohio, have invented certain new and useful 5 Improvements in Plows; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to plows; and it consists in the peculiar construction, combination, and 15 arrangement of the parts, as hereinafter more specifically set forth.

In the drawings, Figure 1 is a side elevation of my device. Fig. 2 is a detached view, showing the plow-point and mold-board. Figs. 3, 20 4, 5, 6, and 7 are detached views, showing under side of beam, brace, clamping-brace, beam-plate, and horizontal plate.

A represents a metallic plow-standard having shoulder a' in contact with the rear of the 25 plow-point e , and provided with the bracket a , for holding it rigidly to the mold-board. It has also the heel b' , forming a part of the landside, where it is secured to the handle d' by the screw-bolt and standard D. It is also rigidly secured to the plow-point by the brace B, which is rigidly bolted thereto by means of the longitudinal plate b .

The standard and plow-point brace B is constructed on its upper or inclined side to conform to the shape of the plow-point, and it is provided with the vertical projection e' , which in part comprises the landside, and acts as a continuation of the landside in a horizontal plane. The longitudinal plate b is inclined at 35 its point to correspond with the plane of that part of the plow-point, and it is rigidly secured to the standard by screw-bolts f' , the heads whereof are located in the space intermediate between the plow-point and the landside.

C marks a clamping-brace, which is rigidly 45 secured to the plow-point and to the mold-board by bolts and rivets, as shown, and it is designed to aid in rigidly securing and holding said parts in proper position.

The beam G is provided with shoulder h' , 50 for the reception of the handle d' , and it is secured thereto by the U-shaped horizontal clamp h , which fits into a slight recess, i , formed in the beam, the said horizontal clamp being threaded at its ends for reception of 55 nuts which are screwed against washers.

$f f$ represent threaded bolts projecting through orifices provided in the horizontal plate E and through the beam G, and secured by the nuts $a'' a''$, which are screwed against 60 the metallic washers $b'' b''$.

The plate E is located in a corresponding recess, g , provided in the beam, and has, in addition to the orifices for reception of the bolts $f f$, the orifices $c c$ for reception of projecting pins which are cast upon the standard A; or a small slot may be formed in said plate for reception of a corresponding projection provided upon the standard. 65

What I claim is—

1. The point e , having its front half bent at a sharp right angle, forming a horizontal share and a colter, which also forms the forward section of the landside, substantially as shown and described. 70

2. The combination of the point e , the angular block B, forming the middle section of the landside, the standard A, having heel b' and bracket a , and the plate b , substantially as shown and described. 75

In testimony that I claim the foregoing as my own I affix my signature in presence of two witnesses. 80

THOMAS FRANKLIN JONES.
